UNITED STATES PATENT OFFICE.

CHARLES WILLIS TANDY, JR., OF CHARLOTTESVILLE, VIRGINIA.

ROTARY ENGINE.

No. 830,023.

Specification of Letters Patent.

Patented Sept. 4, 1906.

Application filed January 25, 1906. Serial No. 297,818.

To all whom it may concern:

Be it known that I, CHARLES WILLIS TANDY, Jr., a citizen of the United States, residing at Charlottesville, in the county of Albemarle and State of Virginia, have invented 5 certain new and useful Improvements in Rotary Engines, of which the following is a specification.

My invention has relation to rotary engines wherein the piston travels in an annular chamber or cylinder, the rotation of the piston being caused by the admission of the motive fluid behind the piston.

Reciprocatory movement of the abutment where low piston speed is desirable has been successful because of the ample time afforded by the abutment movement; but when high-speed engines of this type are desired the time period for abutment movement assumes such small proportions that the desired operation of the abutment cannot keep pace with the piston speed. The rapid reversal of movement of the abutment gives use to strains and vibrations in the apparatus, 25 which is a serious objection.

My present invention has for one of its objects the production of a rotary engine of compact and simple construction and relatively light weight capable of moving at a 30 high rate of speed with a minimum of jar or vibration and possessing a very high efficiency.

Some of the most important advantages afforded by the use of my improved rotary engine may be briefly enumerated as follows: an engine in which every essential part rotates about an axis; vibration reduced; movable parts not reciprocatory, consequently energy saved; movable abutment 40 crossing cylinder perpendicularly to path of piston - head; abutment strengthened by guard-rim, relieving the distortion of centrifugal force, and engine strengthened by compactness.

In the accompanying drawings, in which like parts are designated by like characters throughout the several views, Figure 1 is a vertical longitudinal sectional view of my invention cut on the line X X of Fig. 2. Fig. 2 45 is a top plan view of my invention. Fig. 3 is a cross-sectional view cut on the line Y Y of Fig. 2 when the piston-head is opposite its position in said figure. Fig. 4 is a side elevation of the admission-valve and valve-cham-

ber, the front wall of the said chamber being 55 removed, and sectional view of a steam-chamber provided with a steam-conveying pipe which is broken away, which is secured to said chamber. Fig. 5 is a cross-sectional view of Fig. 4 cut on the line Z Z thereof. 60

My invention is described as follows: The numeral 1 represents my improved rotary engine, the annular chamber 2 thereof being made in two separate members 3 and 4, each of which is provided with a three-fourths 65 circular flange 5, provided with a series of perforations 6, and terminates at its lower end in an outwardly-extending base-section. Said members 3 and 4 are secured together by bringing them together in such a manner 70 that their corresponding perforations 6 register and the outer edges of their base-sections run in true alinement and employing bolts 8. When the two said members 3 and 4 are thus secured together, the base-sections thereof 75 are necessarily brought together, providing a substantial, preferably rectangular, oblong-shaped base 7, which may be made stationary with a floor by bolts 9. The inner parts of 80 said chamber members terminate in oppositely-disposed circular flanges 10, by means of which said members are secured to the outer faces and near the peripheries of two similar connecting members 11, which are oppositely disposed and are each provided with a central 85 large transverse perforation, said members turning outwardly at their inner parts, providing circular flanges 12, which are oppositely disposed. Said member 3 is also provided with a steam-inlet 13 and steam-exhaust 14, the purpose of which will be herein-after shown.

The numeral 15 represents the main axis or shaft, which is provided at that part which passes through the said connecting members 95 11 with two similar integral circular flanges 16. When said shaft is in position, said flanges 16 are in true vertical alinement with said flanges 12, their outer faces being flush with the outer faces of said flanges. A piston 17 is removably secured between and to said oppositely-disposed circular flanges 16 of said shaft 15 at its central perforated part. This is accomplished by providing said projections 16 and said piston 17 near its center 100 with a series of perforations which run around in the form of a circle. The perforations of the piston are caused to register with

corresponding perforations in said projections 16, and they are then securely connected together by bolts 18, provided with the usual nuts 19. Said piston 17 is provided with a 5 piston-head 20, which is removably secured thereto by providing said piston-head with an arc-shaped integral plate 20' and cutting a corresponding recess 20° in the periphery of said piston 17, into which the plate 20' is fitted and secured thereto by bolts 22 or other equivalent means. Said piston-head is adapted to work, when the piston 17 is rotated, in an annular chamber 21, formed by the chamber members 3 and 4. Adjustably 10 secured near the rear end of said shaft 15 by means of an integral collar 23, provided with set-screws 24, is a beveled gear 25, which meshes at right angles with a beveled gear 26, adjustably secured, by means of an integral 15 collar 26', provided with set-screws 26², near the rear end of shaft 27, provided with an enlargement 28, by means of which said shaft is journaled in a vertical bearing 29. Said shaft has also adjustably secured near its 20 front end by means of an integral collar 30, provided with set-screws 31, a gear-wheel 32, which meshes with a gear-wheel 32', secured, by means of an integral collar 33, provided with set-screws 34, near the front end of a 25 shaft 34', working at its front end in a vertical bearing 35 and at its rear end in a bearing 36 integral with and extending outwardly and thence upwardly from the central front end of said base 7. Said shaft 34' is also provided near its rear end with a circular flange 37, which is nearly contiguous with the front face of said bearing 36. This prevents lateral or longitudinal movement of said shaft 34', and consequently diminishes the liability 30 of breakage and reduces vibration. Rigidly connected in any desirable manner to the outer face of said chamber member 3 and one of the connecting members 11 is a cylindrical valve-chamber 38, consisting of side walls 39 and 39', secured together at their inner faces near their peripheries to a cylindrical wall 40. Each of said side walls is provided with a central transverse perforation, corresponding in diameter to diameter of said shaft 15, and with 35 outwardly-extending circular enlargements. Said shaft 15 is journaled in bearings 41. Said side wall 39' is also provided with a circular transverse perforation 42, in which may be secured one end of a steam-inlet pipe 43. 40 Rigidly connected to said main shaft 15 within said valve-chamber 38 is a valve 44, having secured to one end an arc-shaped cut-off plate 45, which corresponds in width to the distance between the inner faces of said walls 39 and 39' and whose outer face corresponds with the curvature of the inner periphery of said wall 40 of said valve-chamber 38, and secured to its other end two similar balancers 45, which are preferably rectangular, oblong 45 in shape, and opposite each other. Said wall

40 is provided in its front end with a steam-outlet 46 in the nature of a perforation or slot and has secured to its outer periphery and at its front end a steam-chamber 47 provided with a circular perforation in which 50 may be secured one end of a steam-conveying pipe 48, the purpose of which will be herein-after shown. Rigidly connected to said shaft 34' by means of a circular integral flange 49 thereof and bolts 50, provided with 55 nuts 51, is a drive-wheel 52, and secured in any substantial manner to said drive-wheel is a rotating abutment or cylinder 53, the inner periphery of which conforms with the periphery of said drive-wheel. The inner or 60 open end of said rotating abutment 53 works in a guard-rim 54, which is integral at its lower part with said base 7 and extends around said abutment continuously. The function of said rim is to prevent lateral motion of said cylinder and to relieve the distortion of the centrifugal force generated when said cylinder is put in rotation. Said open end of said cylinder is also provided with a circular groove in which is placed a friction-reducing agent 54', such as packing. Said cylinder is also provided with an opening 55. (Shown by dotted lines in Fig. 1.) Said piston 17 and abutment 53 are so geared in relation to each other that the abutment presents its opening 55 at the point of intersection of the piston-head 20 with said cylinder and permits the piston-head to pass. The abutment rotates at right angles with the path described by the piston-head 20 and 65 seals the passing of steam. Said abutment is permitted to pass through the chamber members 3 and 4, because of an opening provided therein, and the friction that would be necessarily generated is reduced to a minimum by the use of a friction-reducing agent 55' in the nature of steam-packing or otherwise. A balancer 56 (shown in dotted lines in Fig. 1) may be rigidly or removably connected to said shaft 34'. While the balancer 70 is shown secured to said shaft between said gear-wheel 32 and drive-wheel 52, it is not necessarily connected at that particular part of the shaft, but may be secured to any part of the shaft and in any manner desirable. 75 The operation of my engine is as follows: Steam is admitted into the valve-chamber 38 through the circular perforation 42, cut in the wall 39' thereof by means of said steam-inlet pipe 43. It then passes through the 80 steam-outlet 46, cut in the cylindrical wall 40 of said valve-chamber 38, and is then conducted, by means of a steam-conveying pipe 48, to said annular chamber 21 through the steam-inlet 13 in said chamber member 3, 85 and acting on said piston-head 20 with pressure said piston 17 is caused to rotate, the said head traveling in the said annular chamber. This action of the piston 17 effects the 90 rotation of the main shaft 15. The beveled 95

gear 25 thereof meshing with the beveled gear 26 puts said shaft 27 also in rotation, the gear-wheel 32, secured near the front end thereof, meshing with the gear-wheel 32', secured near the front end of said shaft 34' and causing said shaft to revolve and rotate the abutment 53, secured to the rear end thereof by said drive-wheel 52.

I claim—

- 10 1. In a rotary engine, the combination of two separate and substantially similar chamber members 3 and 4, provided each with a three-fourths circular flange 5 and a base-section, and adapted to be secured together and provide an annular chamber 21, provided with a steam-inlet 13 and steam outlet or exhaust 14 and base 7; a piston 17, provided with a removable head 20, which head is made steam-tight with and is adapted to travel within said chamber 21; a valve-chamber 38, secured to said annular chamber member 3; an admission-valve 44, rigidly connected to a shaft 15, and located within said valve-chamber 38; a cylindrical abutment 53, provided with an opening 55, removably connected at its front end to a shaft 34', provided with a gear-wheel 32'; a shaft 27, journaled in a bearing 29, and provided at its front end with a gear-wheel 32 and at its rear end with a beveled gear 26; with means for conveying the motive fluid into the valve-chamber, thence into the said annular chamber 21, through its steam-inlet 13, behind the piston-head 20, of said piston 17, under pressure, causing the piston to rotate; a beveled gear 25, secured to the rear end of said shaft 15, meshing with said beveled gear 26, secured to said shaft 27, the gear-wheel 32 located near the front end of said last-mentioned shaft, meshing with said gear-wheel 32', connected to the rear end of said axle 34', causing said shaft 34' to revolve and rotate the said cylindrical abutment 53, which crosses the annular chamber 21 perpendicularly with the path described by the piston-head 20, and between the steam-inlet 13 and steam-exhaust 14, and seals the annular chamber behind the piston-head, which head crosses said abutment 53 by its opening 55, substantially as shown and described and for the purposes set forth.
- 20 2. In a rotary engine, an annular chamber 21, formed by the union of two concave chamber members 3 and 4, each provided with a three-fourths circular perforated flange 5, and terminating at its lower end in a base-section, and at its inner part in a flange 10; oppositely-disposed circular connecting members 11 secured at their outer faces and near their peripheries to said chamber members 3 and 4; an axle 15, provided with two oppositely-disposed circular flanges 16; piston 17, provided with a removable head 20,

secured at its central part to said flanges 16, and working between said flanges and said connecting members 11; a cylindrical abutment 53, provided with an opening 55; with means for putting said axle 15 in rotation and thereby rotate said piston 17, the removable head 20 thereof working in said annular chamber 21, and crossing said cylindrical abutment 53 at right angles by its opening 55, substantially as shown and described and for the purposes set forth.

3. In a rotary engine, an annular chamber 21 formed by the union of a concave chamber member 3 provided with a steam-inlet and steam-exhaust, and a concave member 4; a piston 17, provided with a removable head 20, said head being adapted to work in said annular chamber 21 when said piston 17 is put in rotation; abutment 53, provided with an opening 55, movable transversely of and with the piston-head path, with means to rotate said piston 17 and abutment 53, said piston-head crossing said abutment 53 by said opening 55, substantially as shown and described and for the purposes set forth.

4. In a rotary engine, a valve-chamber 38, consisting of side walls 39 and 39', said side wall 39' being provided with a steam-inlet 42, and a cylindrical wall 40, provided with a steam-outlet 46; admission-valve 44, provided at one end with an arc-shaped cut-off plate 45 and at its other end with two similar balancers 45', rigidly connected to said shaft 15, and within said valve-chamber 38, with means to put said shaft 15 in rotation, the cut-off plate 45 of said valve 44 passing said steam-inlet 42 during each revolution of said shaft 15, cutting valve off and opening same almost instantaneously, substantially as shown.

5. In a rotary engine, the combination of a cylindrical piston connected to a shaft and provided with a removable head; annular chamber and base formed by the union of two similar chamber members, each provided with a flange and base-section; oppositely-disposed connecting members 11, secured to said chamber members; cylindrical abutment, provided with an opening, and connected to a shaft, with means for rotating the piston and abutment, the head of said piston made steam-tight with and working in said annular chamber, and crossing said abutment by an opening, said abutment rotating about an axis and crossing said annular chamber perpendicularly with the path of the piston-head, substantially as shown and described and for the purposes set forth.

6. In a rotary engine, the combination of an annular chamber 21; connecting members 11; shaft 15, passing transversely through said members; piston 17, provided with removable head 20, connected to said shaft; rotating abutment 53, with means for con-

veying the steam into the annular chamber
21 under pressure behind the piston-head,
which head rotates within the annular cham-
ber and crosses the abutment 53 by an open-
5 ing therein, substantially as shown and de-
scribed and for the purposes set forth.

In testimony whereof I have signed my

name to this specification in the presence of
two subscribing witnesses.
